EJECTOR MECHANISM FOR HEADING
AND LIKE MACHINES

Dennis George Brosecomb, Smethwick, England,
assignor to G. K. N. Group Services Limited,
Smethwick, England, a British company

Application April 18, 1950, Serial No. 156,533
In Great Britain March 19, 1949

8 Claims. (Cl. 74—53)

1

This invention relates to machines in which workpieces, usually in the form of a length of wire or rod, are inserted in a die, with the inner end engaging the end of an ejector pin and the outer end projecting from the die so that heading or other operations can be effected thereon, during which operations the work is supported against endwise movement by the ejector pin, means being provided for moving the ejector pin endwise until its outer end reaches a definite and preselected position so as to eject the work after the conclusion of the operation on each workpiece.

In this kind of machine it is sometimes important that the outer end of the ejector pin when on its outward movement shall not usually project beyond the end of the die because it is usual to provide carrying tools for the workpiece which slide across the end of the die. Further, workpieces of many different lengths may be used in the machine and it is therefore necessary to provide for an adjustment of the ejector actuating means so that the inner position of the outer end of the ejector pin can be adjusted to the correct distance from the end of the die for engaging and supporting the work during the heading or other operation. Hereafter the operation of adjusting the inner position of the end of the ejector pin to suit the length of the work is referred to as "setting," and the operation of moving the ejector pin endwise until its outer end moves to the end of the die is referred to as "operating."

Hitherto in apparatus of the kind referred to it has been usual to provide two separate controls, one for adjusting the setting position and the other for adjusting the travel of the member which actuates the ejector pin, and it has been found in practice that difficulty has been experienced in getting operators to make these two adjustments correctly, with the result that in some cases the driving member is adjusted to have a travel greater than is necessary, with resultant lost-motion in the mechanism. Such lost-motion produces undesirable noise and wear of the parts and heavy momentary accelerations of parts of the mechanism.

The object of the present invention is to overcome these difficulties and to produce a smooth uniform acceleration and deceleration of the movement of the pin at each working stroke.

It is usual in most machines to employ an ejector pin sliding in the die and a separate ejector rod arranged in alignment with it and operating the ejector pin. Hereafter however these two

2

members will be treated as a unit and referred to as the "ejector pin."

According to the present invention adjustment of the setting position and corresponding adjustment of the length of travel of the ejector pin are effected by the operation of a single adjusting member acting upon setting and operating members connected to link mechanism operated by a power-driven driving member.

10 Also according to the present invention a single adjusting member is used for adjusting the setting and operating means for the ejector pin, and such means comprise separate setting and operating levers pivoted on a common axis, said 15 levers being adapted to move together without moving relatively to one another when the mechanism is being set, and the operating lever making an oscillating movement independently of the setting lever when the operating lever is moving 20 the ejector pin and when making its return movement, said levers being connected by a linkage, one link being pivoted to the operating lever and being engaged by an oscillating actuating lever having an arcuate actuating surface which, prior 25 to its working stroke, is concentric with the centre on which the operating and setting levers are pivoted, the operation of setting causing a variation in the distance between the pivot of the actuating lever and the point of contact between 30 the link connected to the operating lever and the actuating surface of the actuating lever, whereby the amount of movement imparted to the operating lever by the actuating lever is automatically varied to suit the setting position of the operating and setting levers.

35 The invention is illustrated in the accompanying drawing, wherein:

Figure 1 is a sectional view in side elevation; and

40 Figure 2 is a section on the line 2—2.

In the construction illustrated the machine comprises a frame or body made in a number of parts 10, 11, 12, 13, 14, 15, which are secured together by means not shown.

45 The parts 10 and 14 provide guides for the ejector pin 16, which is mounted for endwise reciprocation and which is provided with a flange or collar 17 acted upon by a spring 18 bearing against the inner end of a recess 19 in the part 10 and producing the return movement of the ejector pin.

The part 14 is provided with a cylindrical hole 20 in which the work is placed and from which it is ejected by the ejector pin 16.

50 The part 12 of the body is provided with a

threaded hole 21 in which is a threaded sleeve 22 having a non-circular end 23 so that it can be turned to adjust it in an endwise direction, this sleeve 22 being mounted coaxially with the ejector pin 16. Further, at the end the sleeve 22 is provided with a flange 24 and contains a bush 25 in which one end of the ejector pin 16 is guided.

The part 11 of the frame is provided with a pair of spaced lugs 26 carrying a pivot pin 27.

Mounted on this pivot for pivotal movement around its axis are the setting and operating levers. The operating lever is in the form of a bellcrank lever having a primary arm 28 and a secondary arm 29. The primary arm at its end is formed as a fork 30 engaging over the ejector pin 16 and having an arcuate surface 31 engaging one side of the flange or collar 17. The opposite side 32 of the end of the arm 28 is flat.

The setting lever comprises two spaced members 33 each in the form of a bellcrank lever, these members 33 being mounted to turn on the pivot 27 and being situated at opposite sides of the operating lever. The setting lever has two primary arms 34 situated side by side, and in between these arms is fixed a block 35. The arm 34 terminates in a fork 36, one side 37 of which is flat and engages the surface 32 of the operating lever, while the other side 38 of the fork is of arcuate form and engages the end of the brush 25 and flange 24 of the screwed sleeve 22.

The setting lever is provided with a secondary arm 39 formed in two spaced parts.

The secondary arms 29 and 39 are provided with pivots 40, 41. Mounted on the pivot 41 is an actuating link 42 made in two parts arranged side by side, this actuating link being parallel to the secondary arm 39 of the setting lever.

The linkage also includes a control link 43 mounted on the pivot 40 and on a pivot 44 carried by the two parts of the actuating link 42. The control link 43 is parallel to the secondary arm 29 of the operating lever.

The actuating link is extended beyond the pivot 44 and provided with a roller 45 freely rotatable on a pin 46 carried by the two parts of the actuating link. Further, the actuating link 42 is extended at the opposite end, as shown at 47, and provided with a pin 48 upon which three tension springs 49 are mounted. The end of one of these springs 49 is disposed on the pin 48 between the two parts of the actuating link, and the ends of the other two springs 49 engage the ends of the pin 48 on the outer sides of the two parts of the actuating link.

The part 13 of the frame is provided with two upwardly-projecting lugs 50, and secured to the top of each of these lugs is a bracket 51. Pivoted between these brackets on pivots 52 is an actuating lever 53, this lever 53 having an arcuate surface 54 which is engaged by the roller 45. The surface 54 prior to the working stroke of the operating lever is concentric with the axis of the pivot 27. At one side (see Figure 2) the actuating lever is provided with an arm 55 which engages or is provided with one of the pivots 52 and terminates at its upper end in a fork 56 in which a roller 57 is mounted for rotation. This roller is acted upon by a driving cam 58 mounted on a driving shaft 59. At the other side the actuating lever has an arm 60 which carries or engages the other pivot 52. The roller 57 is kept in contact with the cam by the springs 60. The actuating lever 53 is provided with a pair of spaced lugs 61 carrying a pin 62 on which are pivoted

three spring-loaded pins 63; each of these can slide in a tube 64 having a flange 65 and a stem 66 which is located in a block 67 secured to the inner surface of the machine body. The springs 68 act between the flanges 65 and collars 68 on the pins 63 so that the actuating lever 53 is spring-loaded in a clockwise direction, as shown in Figure 1, and the roller 57 is kept in contact with the cam. The cam provides a dwell for nearly one half of each revolution during which the ejector pin is stationary and it provides for a smooth uniform acceleration and deceleration of the movement of the ejector pin at each working stroke.

The lower ends of the springs 49 are attached to a pin 70 carried by the lugs 51.

The setting lever 34, 39 can be adjusted by turning the sleeve 22 by means of the non-circular part 23, and such adjustment alters the position of the outer end of the ejector pin at the inner end of its stroke. This adjustment is transmitted to the operating lever 28, 29 by reason of the fact that the two surfaces 32 and 37 are in contact during setting. Every setting adjustment produces a corresponding adjustment in the length of travel of the operating lever arm 28, as required to ensure that the outer end of the ejector pin moves to the selected position at each operation. Moreover, lost-motion is avoided and the disadvantages arising therefrom are eliminated.

Further, setting adjustments cause the roller 45 to move along the surface 54 so as to increase or decrease its distance from the axis of the pivots 52. As the roller 45 moves towards the said axis the amount of movement imparted to the operating lever arm 28 decreases correspondingly to the setting adjustment which is made.

In operation of the device the driving cam 58 engaging with the roller 57 causes the actuating lever 53 to pivot about its axis 52, compressing the springs 60, and the arcuate surface 54 of the lever being in engagement with the roller 45 of the actuating link 42, the link is moved bodily in an arcuate path determined by a link 43 and the secondary arm 29 of the operating lever, the springs 49 being tensioned as the link 42 moves. Pivotal movement is imparted by the link 42 to the secondary arm 29 of the bell crank operating lever, which lever pivots about its axis 27, the primary arm 28 thereof causing the work-ejecting movement of the ejector pin 16 against the action of the spring 18, whilst the setting lever 33 remains stationary. The springs 18, 49 and 69 return all parts of the mechanism with which they are associated to the "starting" position shown in Figure 1 of the drawing.

What I claim then is:

1. Ejector mechanism for heading and like machines comprising a slidably mounted ejector pin, a setting member for setting the initial position of the pin, an operating member for moving the pin to its ejecting position, link mechanism connected to said setting and operating members, an actuating lever for operating said link mechanism, a driving member for oscillating the actuating lever and a single adjusting member acting on said setting and operating members for simultaneously adjusting the initial position of the setting member and the length of travel of the operating member.

2. Ejector mechanism for heading and like machines comprising a slidably mounted ejector pin, a setting lever for setting the initial position of the ejector pin, an operating lever for moving

the pin to its ejecting position, said levers being pivotally mounted coaxially, and each having a primary arm and a secondary arm, the two secondary arms being disposed in diverging relationship, an actuating link pivoted to the secondary arm of the operating lever, a control link pivoted to the secondary arm of the setting lever, said actuating and control links being pivoted to each other, an actuating lever for operating said link mechanism, a driving member for oscillating the actuating lever and a single adjusting member acting on said setting and operating members for simultaneously adjusting the initial position of the setting member and the length of travel of the operating member.

3. Ejector mechanism for heading and like machines according to claim 2 wherein the two secondary arms and the two links form a parallelogram.

4. Ejector mechanism for heading and like machines according to claim 2 wherein the two secondary arms and the two links form a parallelogram and the actuating lever has an arcuate surface, the centre of which is disposed at the axis of the pivot of the operating and setting levers, said surface being engaged by means on the actuating link,

5. Ejector mechanism for heading and like machines according to claim 2 wherein the actuating lever has an arcuate surface, the centre of which is disposed at the axis of the pivot of the operating and setting levers, said surface being engaged by means on the actuating link, and the driving member is a rotary driving member and engages means on the actuating lever and causes it to oscillate.

6. Ejecting mechanism for heading and like machines comprising a machine body, a slidably mounted ejector pin guided in said body, a collar on said ejector pin, a spring on said pin acting on one side of said collar, a setting lever for setting the initial position of the ejector pin, an operating lever for moving the pin to its ejecting position, said operating lever engaging the other side of said collar, and a single adjusting member acting on said setting and operating members for simultaneously adjusting the initial position of the setting member and the length of travel of the operating member, said adjusting member having screw operated adjustment in relation to the body, said setting lever engaging between said adjusting member and said operating member, link mechanism connected to said setting and operating members, an actuating lever for operating said link mechanism, a driving member for oscillating the actuating lever.

7. Ejector mechanism for heading and like machines comprising a machine body, a slidably

mounted ejector pin guided in said body, a collar on said ejector pin, a spring on said pin acting on one side of said collar, a setting lever for setting the initial position of the ejector pin, an operating lever for moving the pin to its ejecting position, said operating lever engaging the other side of said collar and a single adjusting member acting on said setting and operating members for simultaneously adjusting the initial position of the setting member and the length of travel of the operating member, said adjusting member being formed by a sleeve screwing into said body, said sleeve being in line with said ejecting pin, said setting lever engaging between said adjusting member and said operating member, link mechanism connected to said setting and operating members, an actuating lever for operating said link mechanism, and a rotary driving member producing oscillation of said actuating lever.

8. Ejector mechanism for heading and like machines comprising a machine body, a slidably mounted ejector pin guided in said body, a collar on said ejector pin, a spring on said pin acting on one side of said collar, a setting lever for setting the initial position of the ejector pin, an operating lever for moving the pin to its ejecting position, said operating lever engaging the other side of said collar and a single adjusting member acting on said setting and operating members for simultaneously adjusting the initial position of the setting member and the length of travel of the operating member, said adjusting member having screw operated adjustment in relation to the body, said setting lever engaging between said adjusting member and said operating member, said levers being pivotally mounted coaxially, and each having a primary arm and a secondary arm, the two secondary arms being disposed in diverging relationship, an actuating link pivoted to the secondary arm of the operating lever, a control link pivoted to the secondary arm of the setting lever, said actuating and control links being pivoted to each other, the two secondary arms and the two links forming a parallelogram and an actuating lever for operating said link mechanism, a driving member for oscillating the actuating lever and said actuating lever having an arcuate surface, the centre of which arc is disposed at the axis of the pivot connecting the setting and operating levers, said surface being engaged by means on the actuating link at a position which can be varied by moving the adjusting member in relation to the body.
